PNEUMATIC ACTION FOR REED ORGANS

Filed Jan. 10, 1922

Percy Preston,

Inventor.

By C. Snowdon.

Attorney.

UNITED STATES PATENT OFFICE.

PERCY PRESTON, OF ARDMORE, OKLAHOMA.

PNEUMATIC ACTION FOR REED ORGANS.

Application filed January 10, 1922. Serial No. 528,179.

To all whom it may concern:

Be it known that I, PERCY PRESTON, a citizen of the United States, residing at Ardmore, in the county of Carter and State of Oklahoma, have invented a new and useful Pneumatic Action for Reed Organs, of which the following is a specification.

This invention relates to a pneumatic action for reed organs and more especially to an action adapted to be controlled by the keys of a piano keyboard so that the reeds of the organ unit placed in the lower portion of a piano can be sounded.

One of the objects of the invention is to provide means whereby the keys of the keyboard will be given an organ touch when the organ is to be played but will have the ordinary piano touch when the organ unit is not being played.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawing which is a section through the structure constituting the present invention, the preferred form of the apparatus has been shown in position to act when a key is depressed.

Referring to the drawing by characters of reference 1 designates the head key of an ordinary piano keyboard. This key is normally spaced from a tracker 2 so that it can be depressed without operating the tracker. A casing or conduit 3 is adapted to be extended throughout the length of and below the keyboard and has an air passage 4 therein. Arranged along the conduit 3 is a series of cells one of which has been indicated at 5, each cell being in communication with the air passage 4 through a port 6. Another port 7 extends from each cell through the top of the conduit and is provided with a valve 8 to which is connected one end of a pin 9 arranged longitudinally within the port 7. A valve 10 is mounted on that end of the tracker 2 extending into the cell 5 and is adjustably attached thereto by a washer 11 of leather or the like screwed onto the tracker. A spring 12 serves to hold the valve 10 normally upon its seat and

when the valve is thus situated both the port 6 and the port 7 are closed thereby.

A tube 12' connects each port 7 with a pneumatic 13 supported on the air chest 14 and extending from the air chest are reed and pipe cells 15, 16, 17 and 18 having ports 19, 20, 21 and 22 through which air is designed to pass into the air chest after vibrating the reeds shown generally at 23.

A valve 24 is mounted in the air chest and is connected by the tracker 25 to the pneumatic 13. Springs 26 serve to hold the valve 24 normally seated to close the air ports and adjustable stops 27 serve to limit the movement of the valve.

Arranged under the conduit 3 is a pneumatic 28 suitably connected to the air passage 4, as by means of a tube 29. The upper portion of the pneumatic is stationary, being connected to a rail A or the like while the lower portion is movable and is connected by one or more rods 30 to the conduit 3. This conduit is pivotally mounted, as shown at 31. Obviously, therefore, when it is designed to use the apparatus for the purpose of playing or vibrating the reeds, a suction is set up through the passage 4 by any suitable means not shown whereupon the pneumatic 28 will be collapsed and the conduit 3 raised so as to bring each tracker 2 against its key 1 to give the keys of the keyboard an organ touch. As a constant partial vacuum is maintained in the passage 4 it will be apparent that when any one of the keys 1 is depressed its valve 10 will be unseated and a suction will be set up from the pneumatic 13 through tube 12 and port 7 to the cell 5 and thence by way of port 6 to the passage 4. The collapse of pneumatic 13 will result in the unseating of the valve 24 and the sounding of the reeds controlled thereby, this sounding being due to the inrush of air through the pipes and past the reeds to the ports 19, 20, 21 and 22. When the key 1 is released the valve 10 will be automatically seated and the pin or tracker 9 will open the valve 8 so as to allow the air to break the suction. When the suction through passage 4 is stopped, the conduit 3 will lower automatically so as to move the tracker 2 away from the key 1. Thus the piano touch of the key will be restored.

What is claimed is:—

1. The combination with a key of a piano keyboard, of a movably supported conduit thereunder, a pneumatic in communication

- with the interior of the conduit and connected to said conduit, an air chest, reed pipes mounted thereon, a valve for controlling the flow of air past the reed pipes, a pneumatic 5 connected to the valve, a tube connection between the conduit and said pneumatic, a valve for controlling the flow of air from said tube into the conduit, and a tracker carried by the valve and adapted to be actuated 10 by the key, the pneumatic connected to the conduit being collapsible by the creation of a partial vacuum within the conduit, thereby to shift the conduit and position the tracker against the key.
- 15 2. The combination with a key of a piano keyboard, of a structure movably mounted thereunder and having an air passage, a pneumatic connected to said structure and in communication with the passage, said 20 pneumatic being collapsible by the creation of a partial vacuum in the air passage thereby to shift the structure relative to the key, a reed pipe, a valve therefor, a pneumatic for controlling the operation of the valve, a connection between the pneumatic and the air passage in the movable structure, a valve 25 for controlling the flow of air to said passage, and a tracker connected to the valve and movable with the structure into and out of operative relation with the key of the keyboard.
- 30 3. The combination with a key of a piano keyboard, of means for controlling the sounding of an organ attachment, said means including a movably mounted structure having an air passage, a valve in said structure for controlling the flow of air to the passage, a tracker connected to the valve and extending from the structure, and a pneumatic 35 connected to said structure to operate it, said pneumatic being in communication with the air passage, said pneumatic being collapsible by the withdrawal of air from the air

passage thereby to shift the tracker into operative relation with the key of the keyboard. 45

4. The combination with a key of a piano keyboard, of means for controlling the sounding of an organ attachment, said means including a structure movably mounted and having an air passage therein, a valve for controlling the flow of air to the air passage, a tracker extending from the valve and beyond the structure, a pneumatic connected to said structure to operate it, said pneumatic being in communication with the air passage, said tracker being shiftable by the flow of air in one direction through the air passage thereby to move the tracker into operative relation with the key of the keyboard. 55 60

5. The combination with a key of a piano keyboard, of a conduit pivotally mounted, sounding reeds, a valve for controlling the flow of air past the reeds, a pneumatic connected to the valve, a second pneumatic connected to the conduit and adapted, when collapsed, to shift the conduit out of normal position, a valve controlling tracker carried by the conduit and shiftable thereby into contact with the key, a tube connection between the first named pneumatic and the conduit and normally cut off from the interior of the conduit by the tracker valve, a valve for closing communication between the tube and the external atmosphere, and means carried by the tracker valve for holding the other valve normally open. 65 70 75

In testimony that I claim the foregoing as my own, I have hereto affixed my signature in the presence of two witnesses. 80
